(57) **CLAIM**

The ornamental design for a monitor camera, as shown and described.

DESCRIPTION

FIG. 1 is a top perspective view of a monitor camera, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof;

FIG. 10 is an enlarged detail view of area 10 in FIG. 1 thereof; and,

FIG. 11 is an enlarged detail view of area 11 in FIG. 2.

The broken lines in the drawings depict portions of the monitor camera that form no part of the claimed design.

The broken lines encircling an enlargement portion of the design forms no part of the claimed design.
